(57) **CLAIM**

The ornamental design for an electric washing and drying machine set for laundry purpose as shown and described.

DESCRIPTION

1. Electric washing and drying machine set for laundry purpose

1.1 : Perspective

1.2 : Front

1.3 : Back

1.4 : Left

1.5 : Right

1.6 : Top

1.7 : Bottom

1.8 : Reference view

The broken lines depict portions of the electric washing and drying machine set for laundry purpose that form no part of the claimed design; as shown in reproduction 1.8, electric washing and drying machine set can be controlled at once by the display at the front center of the claimed design; repro-

(Continued)

duction 1.8 is a reference view showing the state that the display at the front center of the claimed design has been operated.
